(57) **CLAIM**

The ornamental design for a mixing container lid, as shown and described.

DESCRIPTION

FIG. 1 is a top, front and right side perspective view of a mixing container lid showing my new design;

FIG. 2 is a bottom, rear and left side perspective view thereof;

FIG. 3 is a top view thereof;

FIG. 4 is a bottom view thereof;

FIG. 5 is a left side view thereof;

FIG. 6 is a right side view thereof;

FIG. 7 is a rear view thereof;

FIG. 8 is a front view thereof;

FIG. 9 is an exploded top, rear and right side perspective view thereof, shown in an alternate condition of use with an exemplary container;

FIG. 10 is an assembled top, front and right side perspective view thereof; and,

FIG. 11 is a bottom perspective view thereof, with the exemplary container removed.

The broken lines represent both environmental subject matter of an exemplary container, as well as parts of the mixing container lid, none of which form part of the claim.

1 Claim, 12 Drawing Sheets
